T. S. C. Lowe INVENTOR:

UNITED STATES PATENT OFFICE.

THADDEUS S. C. LOWE, OF NORRISTOWN, PENNSYLVANIA, ASSIGNOR TO THE GUARANTEE TRUST AND SAFE DEPOSIT COMPANY, TRUSTEE, OF PENNSYLVANIA.

APPARATUS FOR THE MANUFACTURE OF GAS.

SPECIFICATION forming part of Letters Patent No. 396,338, dated January 15, 1889.

Application filed July 2, 1885. Serial No. 170,465. (No model.)

To all whom it may concern:

Be it known that I, THADDEUS S. C. LOWE, a citizen of the United States, residing at Norristown, Montgomery county, Pennsylvania, 5 have invented a new and useful Improvement in Apparatus for the Manufacture of Water-Gas, of which invention the following is a specification.

This invention is a modification of the apparatus described in my pending application, 10 filed November 12, 1884, Serial No. 147,764.

In order to obtain the best results in producing light from water-gas by incandescence it is necessary that the water-gas shall be free 15 of volatile carbon. It is desirable to be able to make water-gas by the use of inexpensive fuels.

The object of this invention is the production of water-gas by the use of sawdust, 20 pine wood, bituminous coal, or other comparatively inexpensive carbonaceous materials. To effect this result I employ two controllably-connected chambers. In one of these 25 chambers the more inexpensive fuels above referred to are employed for the decomposition of steam, the resulting gases containing volatile carbon. In the other chamber anthracite coal, hard coke, charcoal, or other combustible materials, as free as possible 30 from volatile carbon, (preferring anthracite coal,) are kept in a state of incandescence for the purpose of removing the volatile carbon from the gases produced in the first-named chamber or main generator.

35 The apparatus employed in carrying out my process is represented in the annexed drawings, in which—

Figure 1 is a vertical section of the complete apparatus on the line X X of Fig. 2, and 40 Fig. 2 a horizontal section of the same on the line Y Y of Fig. 1.

The main generator consists of an iron shell lined with fire-bricks or other refractory materials and provided with fire-grate bars 45 or a fire-brick arch over an ash-pit at the bottom.

The main generator comprises the fuel-space A, steam-superheater B, consisting of several layers of fire-bricks or other refrac-

tory materials loosely laid, and a steam-generator, C, consisting of several layers of metal bars crossed and laid loosely, a water-spraying nozzle, D, and a pipe, D', leading to a water or steam supply, all as described in my pending application above mentioned. 50

E is a chamber consisting of an iron shell lined with fire-bricks or other refractory materials and provided with grate-bars F, of metal or fire-bricks, with an ash-pit below. 55

G is a flue connecting the two chambers A and E at the bottom.

H is a valve for closing and opening the flue G.

I and J are valves through which an air-blast is admitted to the fuel in the respective 60 chambers.

K K' K² K³ are flues, of which the flues K K' K² connect the chamber E with the chamber A at the top, and the flues K K' K³ conduct gases from chamber E to a heat-restorer 70 constructed as described in the pending application above mentioned, or to a washer, scrubber, and holder, or directly to the place of consumption, as may be desired.

L and L' are valves for regulating the passage of gas through the flues K² and K³. 75

M is an opening in the upper part of the fuel-space A for admitting an air-blast for the purpose of burning the gases arising from the fuels in chambers A and E while heating the 80 apparatus.

N and N' are doors through which the chambers A and E are charged with fuels.

O is a valve for allowing the products of combustion generated while heating up the 85 apparatus to escape to the atmosphere.

P is a pyrometer for determining the heat in the upper part of the superheater.

Q is a steam-pipe provided with a cock for conducting superheated steam from the upper 90 part of chamber A into the flue G, and R is another steam-pipe provided with a cock for admitting steam into the ash-pit of chamber A, both or either of these pipes being used as desired, for the purpose of mixing steam with 95 the gases passing from the generator A before these gases pass through the fuel in chamber E.

When it is desired to put this apparatus into operation, valves H and L are closed and valves L' and O are opened. An air-blast is then admitted through valves I and J to the 5 fuels in chambers A and E. The unburned gases arising from these chambers are burned by air-blasts admitted at M, heating the fire-bricks B to a high degree and the metal bars C to a considerable degree sufficient, when 10 to desired, to generate steam or to evaporate water into steam. When the fuels in chambers A and E have become sufficiently heated, valves O and L' are closed, as well as the valves admitting air-blast to various parts of the apparatus, while valves H and L are 15 opened. Steam, or water for the production of steam, is then admitted through pipe D', and after the same has passed over the surfaces of the heated materials occupying the upper 20 portion of the chamber A passes as highly-heated steam down through the carbonaceous materials contained in chamber A, and the resulting gas passes out through flue G into chamber E and up through the anthracite 25 coal or other solid carbonaceous materials contained in chamber E, and thence off through flues K, K', and K² to the washer, scrubber, and holder or directly to the place of consumption, passing in any case, if desired, 30 through a heat-restorer. The effect of this operation is to decompose the steam in chamber A, and in so doing, when sawdust, pine 35 wood, bituminous coal, or other materials containing volatile carbon are there employed, the resulting gases containing more or less 40 surplus carbon, which is carried along with the other gases from this chamber into the chamber E, and on passing up through the fuel 45 therein—such as anthracite coal, hard coke, or charcoal in a highly-heated condition—the effect is that the surplus carbon carried in the gas from chamber A is deposited on the highly-heated surfaces of the more solid carbons in chamber E, thereby producing gas 50 composed of carbon monoxide and hydrogen free from surplus carbon, a product which, for many uses in the arts, is exceedingly desirable.

The carbon deposited on the surfaces of the 55 hard fuel in chamber E serves to a great extent to heat itself again when the air-blast is turned on and to prevent the rapid combustion of the more expensive fuels contained in this chamber.

55 In cases where a very large amount of surplus volatile carbon escapes with the gases from generator A it is sometimes desirable to

mix with such gases before they pass through the generator E a limited amount of steam, preferably highly superheated, the result of 60 which is the absorption of the surplus volatile carbon and the production of a larger amount of carbonic oxide and hydrogen—the kind of gas most desired—the resulting gases being thus prevented from containing the objectionable volatile carbon. Steam for this purpose may be admitted at will into the ash-pit of either generator or into the passage-way 65 between the generators, where it will be mixed with the gases from generator A, or it may be admitted by so regulating the valve L' that a portion of the superheated steam from the superheater in generator A may pass in by pipe 70 Q and mix with the gases resulting from the decomposition of the steam passed through 75 the coal in generator A; or, instead of passing the steam down through the coal in generator A, the valve H between the generators A and E can be closed and steam admitted to the ash-pit of generator A and passed up through 80 the fuel in this generator, while another supply of steam or spray of water for the generation of steam may be admitted at the top of the superheater, whereby the steam is brought into contact with the gases from the fuels and 85 afterward passed together through the incandescent fuel in chamber E.

Instead of placing the piled materials for generating and superheating steam, or either of these purposes, in the upper part of chamber A, as above described, they may be placed 90 in a separate chamber connected by flue with generator A.

I claim—

In an apparatus for making water-gas, the 95 combination of a main generator comprising the fuel-chamber A, the steam-superheater B, and the steam-generator C, all inclosed by a single upright shell having an ash-pit and steam-inlet at the bottom, an air-blast inlet at 100 the upper part of the fuel-space, and a valve, O, and water-spraying device D above the steam-generator, a separate generator or fuel-chamber, E, a flue, G, connecting the ash-pits 105 of the chambers A and E, the valve H and valved air-inlets I J, located in the flue G, the valved flues K K' K², connecting the chambers A and E at the top, and a steam-pipe, Q, connecting the flues K² and G, substantially as described.

T. S. C. LOWE.
